US0D1059293S

(12) **United States Design Patent** (10) **Patent No.:** **US D1,059,293 S**
(45) **Date of Patent:** **** Jan. 28, 2025**

(54) **SMART PLUG**

- (71) Applicant: **Amazon Technologies, Inc.**, Seattle, WA (US)
- (72) Inventors: **Alexsandra M. Bowers**, Fairview Park, OH (US); **James Siminoff**, Pacific Palisades, CA (US); **Mark D. Siminoff**, Mountain View, CA (US); **David Brett Levine**, Chagrin Falls, OH (US); **Michael V. Recker**, Gaithersburg, MD (US); **Ryan David Hruska**, North Royalton, OH (US); **Wen-Yo Lu**, Pasadena, CA (US); **Blake W. Gowing**, Chesterland, OH (US)

- (73) Assignee: **Amazon Technologies, Inc.**, Seattle, WA (US)

(**) Term: **15 Years**

(21) Appl. No.: **29/867,802**

(22) Filed: **Nov. 8, 2022**
